UNITED STATES PATENT OFFICE.

ROBERT LEE SKINNER, OF LE ROY, NEW YORK.

MARKING-MACHINE.

1,362,443.

Specification of Letters Patent. Patented Dec. 14, 1920.

Application filed April 1, 1918. Serial No. 225,881.

To all whom it may concern:

Be it known that I, ROBERT LEE SKINNER, of Le Roy, in the county of Genesee and State of New York, have invented certain new and useful Improvements in Marking-Machines; and I do hereby declare the following to be a full, clear, and exact description of the same, reference being had to the accompanying drawings, forming a part of this specification, and to the reference-numerals marked thereon.

My present invention relates to automatic machinery and more particularly to machines for stamping or marking packages or similar articles such as metal cans in which foods are preserved and which it is desired to identify with date, grade or other marks. The invention has for its object to provide a simple, efficient and durable machine of this character that will work smoothly and accurately even at high speed and which will be convenient to the operator who supplies and regulates it. A further object of the invention is to provide a machine in the nature of an attachment or auxiliary that may be applied to other automatic machinery performing previous operations on the same articles and which may be readily combined with such machines and work in harmony with them. To these and other ends the invention resides in certain improvements and combinations of parts all as will be hereinafter more fully described, the novel features being pointed out in the 35 claims at the end of the specification.

In the drawings:

Figure 1 is a side elevation of a can marking machine constructed in accordance with my present invention, showing the position 40 of the parts when moving the stamp in contact with a can;

Fig. 2 is a similar view with the driving mechanism removed, showing the position of the parts when moving the stamp in contact with the inking device;

Fig. 3 is a top plan view of the machine with parts in position corresponding to Fig. 1;

Fig. 4 is a transverse vertical sectional view on the line 4^a—4^a of Fig. 1;

Fig. 5 is a similar view on the line 5^a—5^a of Fig. 1;

Fig. 6 is a longitudinal vertical sectional view on the line 6^a—6^a of Fig. 3, showing 55 the position of the parts at the instant the stamp contacts with a can;

Fig. 7 is a similar view on the line 7^a—7^a of Fig. 3;

Fig. 8 is a detail vertical sectional view on the line 8^a—8^a of Fig. 1;

Fig. 9 is a detail view on the plane 9^a—9^a of Fig. 2, showing the manner in which the can retaining dog trip pawl passes on the return movement of the stamp carrying slide;

Fig. 10 is a detail side elevation of the overhanging arm on the stamp carrying slide, and

Fig. 11 is an enlarged end view of the stamp removed.

Similar reference numerals throughout the several views indicate the same parts.

The machine illustrated in the present embodiment of the invention is designed particularly for applying grade marks to tin cans by means of an inked type and the description, for the sake of clearness, will be limited to this application of the invention, although it will be understood that certain features thereof are applicable to machines differing in the nature of either the marking device or the articles acted upon.

It is the usual practice in canning factories to apply distinctive marks or brands to the cans after they have been sealed, indicating the grade or other characteristic of the contents. The present machine is adapted to receive the cans in continuous succession from such sealing machine, mark them and then pass them on to another machine or deliver them as may be desired. In the preferred embodiment illustrated, each can is halted for a very brief period, at which time it is engaged by the marking element while a carrier that moves the latter back and forth between the marking position and the inking position is also at a point of rest. There is therefore no wiping action between the marker and the can although the machine is adapted to work at such a speed that neither the carrier nor the can appears to rest at all. A similar movement is accomplished in engaging the marking or stamping element with its inking device and for the same purpose.

In the drawings, 1 represents a conveyer that presents the can to the stamping mechanism and that consists of three belts running in spaced relation over pulleys 2 and 3 carried in bearings in a table embodying 110 the parallel longitudinal members 4 supported upon suitable legs 4^a and connected

by the horizontal portion 5 which extends beneath and supports the upper stretch of the belt. The cans may be fed to the conveyer as received from a sealing or other machine performing a previous operation thereon. The pulley 3 is located beneath the table 5^a of the sealing machine, so that cans transferred from the latter to the belt are carried thereby and delivered to a shelf 6 or cross-piece 6 of the table 4. The cans rest successively on the shelf 6 while the stamp is applied thereto, and in order to prevent the other cans on the conveyer from pushing against and displacing the can on the shelf, I provide a detent consisting in this instance, of a pair of arms 7 carried by a rock shaft 8 and normally held with their free ends slightly above the plane of the top of the belt by a spring 9, grooves 2^a being provided in the pulley 2 to accommodate the arms 7. When in raised position, the detent engages the second can B and holds it and the successive cans against movement, the belt 5 meantime slipping beneath the cans. After the stamp has been applied to the can A (Fig. 7), the latter is ejected from the shelf 6 by means of a pusher 10, engaging at its rear side, and slides down an inclined portion 11 of the table 4 upon a belt carrier 12 which travels over a horizontal support 13 and pulleys 14 (only one of which is shown in Fig. 7) mounted in suitable bearings on the longitudinal members 4. The detent 7 is simultaneously withdrawn allowing the belt to advance the can B to the ledge 6, the detent springing up after can B has passed and engaging in front of C, the cylindrical contour of the cans permitting the ends of the arms 7 to rise between the cans B and C as will be apparent. The mechanism for actuating the pusher 10 and detent 7 will be described in detail later.

The stamping mechanism is arranged on a support to one side of the belts 1 and 12, the support in this instance embodying a frame consisting of spaced horizontal members 15 connected by vertical bars 16. The frame is vertically adjustable upon stationary upright posts 17 which also serve to support the inner longitudinal member 4, by means of bolts 18 in the frame passing through slots 19 in the posts, for the purpose of allowing the stamping mechanism to operate upon cans of different length.

The stamp which applies ink to the can is carried by an intermittently movable carrier which has two rest positions, one when the stamp is in position to make an impression on the can and the other when the stamp is in position to engage an inking device or pad.

In the present instance, I provide a reciprocating stamp carrier 20 movable in

ways 21 in the proximate edges of the horizontal members 15 of the supporting frame, and connected by means of a pitman 22 to a crank pin 23 on a disk 25 carried by a shaft 26 which is rotatably mounted in a bearing bracket 27 fastened to the frame at 28. The shaft 26 carries a sprocket 29 which is driven by a chain 30 passing over a sprocket 31 on the shaft 32 of the pulley 1 and also over an idler sprocket 33 carried on a lever 34 which may be secured in position to hold the chain tight by means of a bolt 35 passing through a segmental slot 36 therein. The shaft 32 may be driven from any source of power by means of a chain (not shown) passing over the sprocket 37.

The carrier 20 has a laterally extending arm 38 passing over the top of the can when in position A and the stamp 39 is vertically movable in a recess 40 extending through the outer end of the arm 38. The stamp may be moved vertically by means of a horizontally arranged lever 41 pivoted at 42 between ears 43 on the arm and provided with a pin 44 at its outer end engaging in slots 44 in upwardly extending ears 45 on the stamp. The free end 46 of the lever is engaged at the proper time by mechanism to be later described, and moved upwardly against the force of the spring 47, thereby forcing the stamp into contact with either the can or inking pad. The pivot pin 42 may be removed to change the type by lifting a pivoted latch plate 48 which has a notch 49 fitting over a reduced portion 50 on the pin. After removal of the pin 42 the lever and stamp 29 carried thereby can readily be detached. The type 51 are carried in a wedge shaped type block 52 sliding in a similarly shaped groove in the stamp, and the type blocks are held tightly in the groove by means of a yielding member such as a strip of rubber 53 secured to the stamp at the bottom of the groove. Upon removal of the stamp 39 the type block can be readily withdrawn and a different one substituted.

The inking device is shown in detail in Fig. 8, and embodies an inking pad 54 secured to the upper side of a ratchet wheel 55 carried by a vertical shaft 56, journaled in an overhanging arm 57 secured to the upper arm 15 of the supporting frame. A helical spring 58 surrounding the shaft bears at one end against the upper side of the arm 57 and at its other end against a nut 59 on the shaft. The spring not only offers a resistance to free rotation of the pad but permits the latter to yield slightly downward as the stamp is forced against it. The wheel 55 is intermittently advanced to bring a fresh portion of the pad beneath the stamp at each impression of the latter, by means of a gravity operated pivoted dog 55^a carried by an

arm 56^a on the stamp carrier 20. When the carrier is moved in one direction the dog engages with a tooth of the wheel and rotates it ahead but passes by the teeth when moved 5 in the opposite direction.

The lever 41 is, in the present instance, actuated by oppositely disposed cam members 60, 60^a secured to a slide 61 movable in guides 62 on an offset portion 15^a of the 10 upper guide members 15. The slide is reciprocated by means of a projection or lug 63 on the crank disk, which makes alternate contact with lugs 64 and 64^a on the slide 61, the lug 64^a being, in the present instance, 15 formed at the lower end of a depending plate 65 secured at its upper end to the slide, and intermediate its ends to a supplemental guide block 66 slidable in the grooves 21. The cam members 60, 60^a are formed preferably 20 of sheet metal with offset inclined portions 67, 67^a respectively projecting into the path of the end 46 of the lever 41, and are so positioned on the slide relatively to the lugs 64 and 64^a that just before the stamp carrier 25 reaches the right hand limit of motion, the lug 63 on the crank disk comes in contact with the lug 64 on the slide 61 and moves the latter toward the left (Fig. 1), bringing the incline 67 of the cam member 60 in contact 30 with the end of the lever. Continued motion of the slide causes the lever to ride up the incline, as shown in Fig. 6, the lever reaching the upper end at the instant that the crank pin 23 is upon the "dead center" 35 in which position the stamp carrying slide is stationary. This position is indicated in Figs. 1, 2 and 6 by the line R. When the end 46 of the lever is at its highest point, the stamp is in contact with the can, and 40 since there is no relative motion between the can, and stamp at this instant, there will be no tendency to blur the impression. The continued movement of the slide brings the incline 67 into the position 67^L in which 45 position the lug 63 passes out of engagement with the lug 64, by reason of the circular path of motion of the former. As soon as the incline 67 has passed beyond the end of the lever, the latter is moved to the position 50 shown by C (Fig. 6) by means of the spring 47, and further movement of the stamp carrier to the right in said figure causes the engagement of the end of the lever on the under side of the incline 67, the 55 lever being depressed to pass by the lower end of the incline. After passing under the incline, the weight of the stamp will return the lever to horizontal position so that the end 46 occupies the position shown at C in 60 Figs. 2 and 6, just before the incline 67^a is moved in contact therewith, by engagement of the lug 63 with the lug 64^a on the slide 61.

With the parts shown in position of Fig. 2, the stamp carrier has almost reached the 65 left hand limit of motion, and the stamp is

positioned above the inking pad. Just at the instant that the crank pin 23 reaches the "dead center" the end of the lever will have reached the upper end of the incline 67^a, this position being indicated in Figs. 1, 2 70 and 6 by L. In this position, the stamp is in contact with the inking pad. Further movement of the cam slide and stamp carrier causes the end of the lever to move under the incline 67^a and finally occupy the 75 position shown at A (Fig. 1), completing the cycle of movement. As the end of the lever passes the under side of the inclines 67, 67^a, the weight of the stamp ordinarily restores the lever to horizontal position as 80 shown in Fig. 5. If, however, it should from any cause stick in the lowermost position, as shown in dotted lines in said figure, the end 46 would not be in position to properly ride up the upper faces of the inclines. 85 In order to insure the proper operation, I provide stationary cams 68, 68^a on the supporting frame adjacent the slide 61 and so arranged with reference to the inclines 67, 67^a that in case the end of the lever as it 90 passes under one of the inclines, for example, the incline 67 (Fig. 6), does not move to position to engage the other incline 67^a, it will engage cam 68^a before reaching the latter incline and be brought into proper position to coöperate with the latter. The cams 68 and 68^a are, in this instance, arranged to one side of the inclines 67, 67^a, so that the reciprocating motion of the latter is not interfered with. When the end of the 100 lever moves under the inclines 67, 67^a, the latter have moved away from the cams a sufficient distance so that there is ample space for the lever to pass between them. 105

After the stamp has been impressed upon the can, the latter is pushed off the ledge 6 by the ejector 10, which, in the present instance, is in the form of a reciprocating plunger guided in ways 69 on a lateral extension 70 of the stamp carrier. The plunger is actuated by means of a gear segment 71 carried by a vertical shaft 72 in the extension 70, and meshing with rack teeth 73 on the plunger. A downwardly projecting pin 74 on an arm 75 of the gear segment 115 engages alternately with stops 76, 76^a on the lower member 15 of the supporting frame when the stamp carrier is reciprocated. When the arm 75 is in the position shown in Fig. 2, the plunger is withdrawn, 120 allowing the outer end thereof to pass by a can in the position A (Fig. 7) as the stamp guide moves toward the right. As the stamp guide approaches the right hand limit of its motion, pin 74 comes in contact 125 with stop 76, causing the rotation of the gear segment and consequent outward movement of the plunger in rear of the can, as shown in Fig. 3. When the direction of movement of the stamp carrier is reversed, 130

the plunger 10 carries the can A ahead, delivering it upon the conveyer 12 as previously described, and just before the carrier reaches the left hand limit of motion, pin 5 74 strikes stop 76^a, withdrawing the plunger so that it can pass by a second can which has meanwhile been deposited on the shelf 6. This last named action is brought about by withdrawing the detent 7 from 10 the cam B at the appropriate time. In order to accomplish this, the rock shaft 8 is extended beyond the side member 13 of the belt table and at the free end, which is reinforced by a bearing 8^a, the shaft carries 15 a crank arm 77 having a laterally offset projection 78 at its outer end. The upper corner of this projection is beveled at 79 to provide a cam surface with which coöperates a similar beveled surface 80 on a cam member 81, pivoted at 82 to a downwardly depending member 83 vertically adjustable on the extension 70 of the stamp carrier, by 20 means of a screw 84 passing through a slot in the slide. It will be seen from Fig. 1 25 that as the stamp carrier moves toward the left, the pawl 81 will engage the projection 78 and move the arm downwardly thereby withdrawing the detent and allowing the belt 1 to carry the can B ahead and deposit it on the shelf 6, the can A having 30 been previously removed by the plunger 10. As soon as cam 81 has passed projection 78, 35 the detent is urged upwardly by its spring 9 in readiness to engage can C as it is fed forward by the belt 1'. Upon the return motion of the stamp carrier, a lateral bevel 85 on the cam 81 engages a similar bevel 86 on the projection 78, thereby swinging the cam 81 about its pivot 82 as shown in 40 Fig. 9, and allowing the passage thereof without withdrawing the detent. After the cam 81 has passed projection 78, it again returns to vertical position in which it is stopped by engagement of coöperating portions 87 and 88 on the cam and slide, 45 respectively.

The operation of the mechanism is as follows: a can transferred from the shelf 5^a of the sealing machine to the belt 1 is carried thereby to position B in which it is held back until the detent 7 is withdrawn. It is 50 then carried by frictional engagement with the belt to position A upon the shelf 6, where it remains stationary while the stamp 55 is being applied thereto, as previously described. While the stamp carrier is moving toward the inking pad, the can A is transferred to the belt 12 and the detent is withdrawn, allowing the next can to be fed forward 60 into printing position. The mechanism is readily adjusted to operate on cans of different length. The clamping bolts 18 for the supporting frame are loosened and then the frame is raised or lowered until the 65 stamp makes a proper impression on the can

top, when the frame is once more clamped in place. This adjustment of the frame necessitates a corresponding adjustment of the tightener sprocket 34, which is obtained by loosening the bolt 35 and moving the arm 70 34 until the slack is taken from the chain, after which the bolt is again tightened. Similarly, the screw 84 is loosened to enable the slide bar 83 to be moved into co-operative relationship with the crank arm 75 77. Guard rails 89 and 90 are provided on opposite sides of the conveyer 1, and the can is preferably moved in contact with the inner rail 90, as it is moved upon the shelf 6, by means of a deflector 91, pivoted to the 80 outer longitudinal member 4 at 92, and projecting over the top of the shelf. A bolt 93 operating in an arcuate slot 94 in the shelf enables the deflector to be adjusted to proper position to accommodate cans of differing diameters and locked securely in position. 85

I claim as my invention:

1. In a marking machine, the combination with a work support embodying a runway 90 for a succession of articles, a stamp and a reciprocatory stamp carrier, of a pitman for imparting movement to the stamp carrier along the runway and means for bringing the stamp and a work piece on the support 95 into engagement while the pitman is on a dead center.

2. In a marking machine, the combination with a work support embodying a runway and means for feeding a succession of 100 articles along the same, an inking device, a stamp and a stamp carrier arranged to reciprocate along the runway, of a pitman for imparting movement to the stamp carrier and means for bringing the stamp and inking device into engagement while the pitman is on one dead center and means for bringing the stamp and an article on the runway into engagement while the pitman 105 is on the other dead center. 110

3. In a marking machine, the combination with a work support, of a stamp, a reciprocatory stamp carrier, a work feeding device on the latter and means for actuating the stamp relatively to its carrier and 115 against an article on the work support while the carrier and feeding device are at the reversing point of their reciprocation.

4. In a marking machine, the combination with a work support, of a stamp, a reciprocatory stamp carrier, a driving wheel 120 and pitman for moving the stamp carrier, and a reciprocatory trip operated by the driving wheel for actuating the stamp toward a work piece on the support while the pitman 125 is on a dead center.

5. In a marking machine, the combination with a work support and an inking device, of a stamp, a reciprocatory stamp carrier, means including a device movable with 130

the latter for feeding work pieces successively to a predetermined position of rest on the work support and means for bringing the stamp in alternate engagement with the inking device and a work piece on the support while the stamp carrier is at the respective reversing points of its reciprocation.

6. In a marking machine, the combination with a work support embodying a runway 10 for a succession of separate articles, and means for feeding work pieces successively to a predetermined position of rest thereon, of an inking device, a stamp, a stamp carrier intermittently movable along the runway and occupying a position of rest when the stamp is in operative relationship with either a work piece or the inking device, and actuating mechanism coöperating with the stamp when the stamp carrier is at rest.
7. In a marking machine, the combination with a work support, of a stamp, a stamp carrier movable on the support, a crank mechanism for reciprocating the carrier, means actuated by the crank mechanism for coöperating with and actuating the stamp when the stamp carrier is at the limits of its motion, an inking device arranged at one such limit, and means actuated by the crank mechanism for moving a work piece to a position at the other limit of motion of the stamp carrier.

8. In a marking machine, the combination with a work support, of an inking device, a stamp, a stamp carrier movable on the support, a crank for reciprocating the carrier, a lever on the carrier for actuating the stamp, and means actuated by the crank mechanism for coöperating with the lever when the stamp carrier is at the limits of its motion.
9. In a marking machine, the combination with a work support, of an inking device, a stamp, a stamp carrier movable on the support, a crank for reciprocating the carrier, a lever on the carrier for actuating the stamp, and cam members moved by the crank mechanism for actuating the lever when the stamp carrier is at the limits of its motion.

10. In a marking machine, the combination with a work support, of an inking device, a stamp, a stamp carrier movable on the support, a crank for reciprocating the carrier, a lever on the carrier for actuating the stamp, a cam slide movable on the support having oppositely inclined cam portions adapted to engage the lever, to deflect it in a direction transverse to that of the motion of the cam slide, and an operating portion on the crank adapted to engage alternately with each of a pair of coöperating portions on the cam slide whereby the cam portions on the latter engage alternately with the lever for actuating the stamp when the stamp carrier is at the limits of its motion.
11. In a marking machine, the combina-

tion with a work support, of an inking device, a stamp, a stamp carrier, a crank for reciprocating the carrier, an operating member on the carrier engaging the stamp, means on the support for engaging the operating member when the stamp carrier is at the limits of its motion, and an operating portion on the crank for actuating the stamp operating member.

12. In a marking machine, the combination with a work support, of an inking device, a stamp, a reciprocating stamp carrier movable on the support and occupying a position of rest when the stamp is in operative relationship with either a work piece or 75 inking device, means for actuating the stamp when the stamp carrier is at rest, a work piece ejector carried by the stamp carrier, and means for projecting the ejector in rear of the work piece at the end of one stroke of 80 the carrier so that the work piece will be carried along the support by the opposite stroke of the carrier.

13. In a marking machine, the combination with a work support, of an inking device, a stamp, a stamp carrier occupying a position of rest when the stamp is in operative relationship with either a work piece or the inking device, means for actuating the stamp when the carrier is at rest, and an 90 ejector carried by the carrier and operating to displace the work piece when the carrier moves from printing to inking position.

14. In a marking machine, the combination with a work support, of an inking device, a stamp, a reciprocating stamp carrier occupying a position of rest when the stamp is in operative relationship with either a work piece or the inking device, an ejector 100 carried by the carrier, and means for moving the ejector into operative relationship with a work piece at the end of one stroke of the stamp carrier and moving it out of operative relationship at the end of the opposite stroke.

15. In a marking machine, the combination with a work support and a conveyer for delivering work pieces onto the work support in position to be printed upon, of a reciprocating member, an ejector carried by 115 the reciprocating member and engaging a work piece on the support when the reciprocating member is moved in one direction, a detent for holding back work pieces on the conveyer, and means for withdrawing the 120 detent when the ejector removes a work piece from the support.

16. In a marking machine, the combination with a work support, of an inking device, a stamp, a reciprocating stamp carrier 125 occupying a position of rest when the stamp is in operative relationship with either a work piece or the inking device, means for actuating the stamp when the stamp carrier is at rest, a plunger transversely movable in 130

the stamp carrier, an oscillatory member on the carrier engaging the plunger and stops on the support coöperating with the oscillatory member whereby the plunger is moved into coöperative relationship with a work piece as the carrier nears the printing position and out of operative relationship as the carrier nears the inking position.

17. In a marking machine, the combination with a work support and a conveyer for delivering work pieces to the support in position to be printed upon, of a reciprocating member, an ejector carried by the reciprocating member and engaging a work piece 10 on the support when the reciprocating member is moved in one direction, a detent for holding back work pieces on the conveyer, and having an operating arm, and a cam member carried by the reciprocating member 15 adapted to engage the operating arm of the detent when moved in one direction but pass by freely when moved in the opposite direction.

18. In a marking machine, the combination with a work support, of a rotary inking pad on the support, a stamp, an intermittently movable stamp carrier occupying a position of rest when the stamp is in operative relationship with either a work piece 25 or the inking device, actuating mechanism coöperating with the stamp when the stamp carrier is at rest, and means carried by the stamp carrier for rotating the pad between impressions of the stamp.

30 19. In a marking machine, the combination with a work support, of an inking device, a stamp, a stamp carrier movable on the support, a crank for reciprocating the

carrier, a lever on the carrier for actuating the stamp, a movable lever actuating member having cam portions thereon which co-operate with the lever to operate the stamp when the actuating member is moving in one direction relatively to the stamp carrier but which pass the lever without actuating 45 the latter when the actuating member is moving in the opposite direction relatively to the stamp carrier, and means for causing the engagement of the cam portions with the lever when the stamp carrier is at the 50 limits of its motion.

20. In a marking machine, the combination with a work support, of an inking device, a stamp, a stamp carrier movable on the support, a crank for reciprocating the carrier, a lever on the carrier for actuating the stamp, a cam slide movable on the support having oppositely inclined cam portions adapted to engage the lever to deflect it in a direction transverse to that of the motion of 60 the cam slide, an operating portion on the crank adapted to engage alternately each of a pair of coöperating portions on the cam slide whereby the cam portions on the latter engage alternately with the lever for actuating the stamp when the stamp carrier is at the 65 limits of its motion, and means for moving the lever after actuation by a cam portion into position to engage the cam portion on the opposite side and pass by the latter 70 without operation of the stamp.
